UNITED STATES PATENT OFFICE

2,589,785

SHOE POLISHING MACHINE

William A. Edington, Shreveport, La.

Original application August 22, 1942, Serial No. 455,786, now Patent No. 2,427,768, dated September 23, 1947. Divided and this application May 10, 1945, Serial No. 593,019.

1 Claim. (Cl. 194—6)

1

This invention appertains to shoe polishing machines generally, and more particularly to the type shown and described in my co-pending application for Letters Patent of the United States, which was filed by me on the 22nd day of August, 1942, Serial No. 455,786, of which this application is a division such application having matured into Patent 2,427,768 on September 23, 1947.

One of the several objects and advantages of the invention is to provide a simplified arrangement of coin and manual controls for the motor drive of the machine, the coin establishing connection between the motor circuit and the electric current source, and the manual controls for setting the motor in motion for the operation of the shoe cleaning and polishing mechanisms.

With this and other objects in view, the invention resides in the certain new and useful combination, construction, and arrangement of parts and circuits, as will be hereinafter more fully described, set forth in the appended claims, and illustrated in the accompanying drawings, in which:

Figure 1 is a rear elevation, with a portion of the back wall broken away to expose to view certain of the mechanism housed within the cabinet;

Figure 2 is an enlarged sectional view, taken through the line 2—2 of Figure 1;

Figure 3 is a vertical sectional view, taken through the line 3—3 of Figure 1;

Figure 4 is an enlarged fragmentary vertical section, taken through the line 4—4 of Figure 1;

Figure 5 is an enlarged detail, in perspective, of the actuating mechanism of the shoe shining cloth or web; and

Figure 6 is a diagram of the electrical circuits.

Referring to the drawings, wherein like characters of reference denote corresponding parts in the several views, the embodiment of the invention, as it is exemplified therein, is comprised in a cabinet 10 having its several walls, including the side walls 14, secured to a frame structure 12, and a bottom wall 28 having casters 16 affixed thereto for the rolling support of the cabinet from one place of use to another. A compartment or chamber 18 is provided in the uppermost part of the cabinet 10 for housing shoe cleaning and polishing accessories within the same, access being had to its interior through front openings normally closed by doors 20. The front side of the cabinet 10 includes an inclined central wall 24 connecting the upper portion below the doors 20 with a lower vertical wall portion 26.

2

Interiorly of the cabinet 10, upon its bottom wall or floor 28, is mounted an electric motor 30 having its rotor shaft 32 provided with a grooved pulley 34 to drive a V-belt 36. The belt 36 connects the pulley 34 with a smaller grooved pulley 38 keyed on a line shaft 40 which is supported in bearings 42 secured on the floor 28. A second grooved pulley 44, approximating the pulley 38 on the line shaft 40 in size, is also keyed on the line shaft 40 and is connected by a V-belt 46 to a large sized grooved pulley 48, which is keyed to a shaft 50 having a crank 52. This shaft 50 is journaled in bearings carried by standards or posts 54 arising from the floor 28.

The crank 52 is provided with a bearing 58 for one end of a pitman or arm 56 which has its other end provided with a channelled cross-arm 60 for the securement of one end of a shoe shining cloth or web 62 in its channel. The web 62 extends upwardly from the cross-arm 60 and has a central portion horizontally disposed and supported by elastic straps 64 engaged on studs or pins 66 projecting from a horizontal frame member 68. The opposite end portion of the web 62 depends from the supporting straps 64 and is secured by a plurality of elastic straps 72 which have their ends clamped between a plate 74 and the floor 28 by means of bolts 76. Thus, the web 62 is of inverted U configuration, as shown in Figure 1, with its bight 78 of sufficient length to provide space between its pendent portions for the positioning of the fore part of a shoe therein for polishing.

A foot support 80 is secured to the lower front wall 26 and one of the posts 54 and extends horizontally beneath the bight 78 of the polishing web 62. A substantially U-shaped spring 84 is mounted on the margin 82 of the heel portion of the foot support 80 and has its uppermost leg 88 engaged by a rod 86, and its other leg 90 provided with an opening 92 through which the rod loosely depends. The rod 86 also loosely depends through an opening 94 formed in the heel margin 82 of the foot support 80 and extends 45 downwardly for connection with the blade 96 of a knife switch 98 that is mounted on the floor 28.

A tension spring 100 has one end connected by a pin 102 to the rod 86 and its other end by a pin 104 to the lower front wall 26. Pressure 50 of the heel of the foot resting on the support 80 on the uppermost leg 88 of the spring 84 depresses the rod 86 to close the switch blade 96 on the contacts of the switch 98 and places the spring 100 under tension and this, upon the 55 removal of heel pressure from the leg 88, of the spring 84, returns the rod 86 to its normally

elevated position, the upward motion of the rod 86 withdrawing the switch blade 96 from the switch contacts to open the circuit on the motor 30.

A coin receptacle or box 106 is mounted within the cabinet 10 and has a hinged bottom 108, which is to be locked in closed position by means of a padlock (not shown) engaged with a hasp 110. A coin chute 112 leads from the receptacle and connects with a receiving slot 114 opening through the inclined wall 24 of the cabinet 10. The coin chute 112 includes front and rear walls 116 and 118, respectively, connected by side walls 120. These walls are made from an insulating material, and the rear wall 118 is hingedly connected, as at 118', with the inclined wall 24, and it, together with the front wall 116, carry electrical conductors 122, substantially as is best shown in Figure 2. These conductors 122 converge in a downward direction, so as to have their lower ends spaced apart sufficiently only to be bridged by a coin passing downwardly of the chute 112 from the receiving slot 114.

Fixedly secured to the rear wall 118, of the chute 112, is a trip arm 124 that has its outer end resting upon a spring stop 126 which is secured to a frame member 128. A tension spring 130 has one end anchored to a side wall of the coin receptacle 106 and its other end to the trip arm 124 to normally hold the latter engaged with the stop 126, the arm 124 being provided with a bumper 132 to absorb the shock incident to its engagement with the stop 126.

A shaft 134 is rotatively supported in bearings 136 mounted on a frame member 138 and carries a ratchet wheel 139 that is engaged with a pawl 140 which is pivoted on a lever 142 having a hub 144, intermediate its ends, rotatively mounted on the shaft 134. A second pawl 146 engages the ratchet wheel 139 and is pivotally mounted on a bracket 148 carried by a frame member 150. By this arrangement, counter-clockwise motion of the lever 142 imparts a similar motion to the ratchet wheel 139 and, consequently, to the shaft 134, the second pawl 146 acting on the ratchet wheel 139 to prevent its clockwise motion.

A tension spring 152 has one end connected with the lever 142 and its other end to a vertical frame member 154. One end of a cable 156 is attached to the lever 142 and passes about a grooved pulley 158 supported from a side of the foot support 80, as best shown in Figures 2 and 5, and downwardly therefrom for connection with a pin 160 carried by the channelled cross-head 60. A tension spring 162 has one end connected to the pin 160 and its other end anchored to the foot support 80. A buffing wheel 164 is keyed on the shaft 40 and extends partially through an opening 166 formed in the lower front wall 26, of the cabinet 10, the extended portion of the buffer wheel and the opening being normally closed by a cover 168 that is hinged, as at 168', to the adjacent side edge of the cabinet.

The electrical circuits of the machine, thus provided, are graphically depicted in Figure 6, and, as shown, lead-in conductors 172 and 174, which may take the form of a conventional electrical cord carrying a plug connector (not shown) for attachment to a wall or other power service outlet, pass to and respectively connect with one of the conductor strips 122 and one terminal of the motor 30. A conductor 176 leads from the other of the conductor strips 122 and

connects with one terminal 178 of the knife switch 98, the blade of which is adapted to engage with the terminal 178, when the rod 86 is depressed by the pressure of the footed shoe on the upper leg 88, of the spring 84, when the foot is resting on the support 80. A conductor 180 leads from the terminal 178 and connects a contact 182 of a manually actuated switch 170, which may be of the snap type, and is mounted exteriorly of the inclined wall 24 of the cabinet 10. The other contact 184, of the switch 170, is connected by a conductor 186 to the other terminal 188 of the knife switch 98, which terminal is in electrical connection with the blade 96 and, by a conductor 190, with the other terminal of the motor 30.

In the operation of the machine, a coin is inserted downwardly of the slot 114 (Fig. 2) and passes downwardly of the chute 112 towards its lower end where it establishes electrical connection between the conductor strips 122. At the same time, a foot is inserted inwardly of an opening formed in the lower front wall 26 to position on the support 80, the said opening being normally closed by a hinged door 192. The toe region of the footed shoe, when properly positioned on the support 80, engages beneath the bight 78 of the polishing web 62, and downward pressure of the heel of the shoe depresses the upper leg 88, of the spring 84, and also the rod 86, causing the switch blade 96 to bridge the contacts 178, 188, of the knife switch 98, and close the circuit on the motor 30. Motion of the rotor shaft 32, of the motor 30, is transferred to the crankshaft 50, the crank 52 of which imparts a reciprocating motion to the arm 56 and through it to the web 62, when the bight portion of the latter will perform its polishing function, it being understood that, prior to the introduction of the footed shoe to the support 80, polishing material will have been applied to the shoe. The bight portion of the web 62 is permitted to act after the manner of a hand manipulated polishing cloth by the yielding action of the elastic straps 64, which readily accommodate themselves to the reciprocating action of the arm 56 connecting the web 62 to the crankshaft 50.

Upon completion of the polishing of the toe portion of the shoe, the sides and back portions thereof are to be polished and, to this end, the cover 168 is moved to open position for the exposure of the protruding portion of the buffing wheel 164, at the outer side of the lower front wall portion 26, so that the foot can be manipulated to present these portions of the shoe to the buffing surface. When making use of the buffing wheel 164, the electrical circuit is closed through the motor 30 by way of the control switch 170 which shunts the line current about the knife switch 98.

Continued operation of the motor 30 now actuates the lever 142 to effect rotation of the ratchet wheel 139 through one revolution, and, through it, the actuation of a coin release mechanism. This mechanism is comprised in a trip 194 that is fixedly secured to the shaft 134 and lies in the path of the spring stop 126. As the trip 194 engages the spring stop 126, the latter is flexed downwardly and, as the trip passes beneath the arm of the spring, the arm recoils and strikes the trip arm 124 and pivots the chute wall 118 away from the front wall 116, thus spreading these walls at their lower ends and releasing the coin from between the contact strips 122. The coin passes from the chute into the receptacle 106.

and breaks the circuit on the motor 30. Access to the interior of the cabinet, below the storage compartment at its upper end, is to be had through two doors 196 hinged, as at 198 on the side walls 14 of the cabinet 10. The two doors 196 when in closed position form the rear wall of the cabinet 10.

Without further elaboration, the foregoing disclosure so fully illustrates my invention, that others may, by applying current knowledge, readily adapt the same for use under various conditions of service.

What I claim is:

A coin-controlled mechanism, comprising an electric motor, a coin chute provided at its upper end with a coin receiving slot and at its lower end with a coin discharging slot, said chute comprising an inclined front wall, side walls extending at right angles from said front wall, a rear wall movable within said side walls and normally inclined with relation to the front wall, means pivoting said rear wall whereby the angularity between the same and said front wall may be varied a predetermined distance sufficient to be bridged by a coin, electrically conducting strips secured to said front wall and rear wall in opposing relationship with the lower ends of said walls spaced apart, a lateral arm having one end fixed to said pivoted rear wall, a flat spring plate underneath said lateral arm in contact with the free end thereof, a tension spring attached to said lateral arm biasing the same into contact with said flat spring plate, a rotatable shaft, a ratchet wheel secured to said shaft, a lever pivoted on said shaft, a pawl pivoted on said lever and driv-
ingly engaging said ratchet wheel, a trip arm fas-
tened to said ratchet wheel and adapted to move

in a path to depress one end of said spring plate to flex the same downwardly whereby upon passage of said trip arm past said spring plate the same recoils upwardly to strike said lateral arm 5 thereby pivoting said rear wall away from said front wall to release the coin therebetween for discharge from said chute, a tension spring connected to said lever, a cable attached to said lever adjacent said latter tension spring, a crank 10 device operated by said motor and connected to said cable for reciprocating the same to oscillate said lever for stepping around said ratchet wheel, a pawl pivoted on the frame member engaging said ratchet wheel preventing retrograde move- 15 ment of said ratchet wheel, a source of electrical energy, a foot actuated switch, and means placing said electrical strips, switch and motor electrically in series whereby a coin bridging the gap between the converging ends of said electrical strips conditions said motor for operation upon closing of the switch.
